UNITED STATES PATENT OFFICE.

NAPOLEON DU BRUL, OF CINCINNATI, OHIO.

CIGAR-BUNCHING MACHINE.

1,002,655.

Specification of Letters Patent.

Patented Sept. 5, 1911.

Application filed June 19, 1909. Serial No. 503,216.

To all whom it may concern:

Be it known that I, NAPOLEON DU BRUL, a citizen of the United States, residing at Cincinnati, in the county of Hamilton and State 5 of Ohio, have invented certain new and useful Improvements in Cigar-Bunching Machines, of which the following is a specification.

My invention relates to machines in which 10 a quantity of tobacco is placed into a hopper and fed in measured charges to a slide which delivers the charges successively to a rolling apron in order to form a cigar bunch and apply the binder thereto.

15 In machines for this purpose, as heretofore constructed, difficulty has been experienced in maintaining uniformity in the size of the charge of tobacco that goes to make up the bunch; it being found that adjustments which insure the desired weight of 20 bunch while the supply receptacle (for example the hopper) is filled with tobacco, produce bunches of less and less weight as the hopper becomes emptied; or, if adjustment is made suitable for a reduced bulk of 25 tobacco in the hopper, the bunches will be too heavy when the measuring pocket is under the influence of a larger bulk in the hopper.

30 One object of the present invention is to prevent undesirable variations in the weight of the bunch, notwithstanding the gradual using up of the tobacco in the supply receptacle.

35 To this end, one feature of the present invention consists in providing a limiting guard or barrier for the pocket which determines the size of the charge leaving the hopper, and keeping the bulk of tobacco 40 above or around the measuring pocket, substantially constant or sufficiently near constant to prevent objectionable variation in the weight of the cigar bunches produced; in other words preventing the measuring pocket coming under the influence of the varying pressure of tobacco in the hopper, the guard or barrier being preferably designed to provide a supplemental or 45 provisional tobacco receptacle surrounding the measuring pocket, and a main receptacle for tobacco in bulk, having such communication as to insure substantially constant depth of tobacco over the measuring pocket in the provisional receptacle or chamber.

50 In the embodiment selected for illustration of the invention, the measuring pocket is

likewise the throat or passage by which the measured charges of tobacco escape to the feed slide. A barrier is preferably located in advance of the opening through the 60 guard in order to prevent choking of the tobacco at the entrance to the guard.

Another object of the present invention is to simplify means for feeding the tobacco to the pocket, to which end another feature of 65 the invention consists in providing a single disk, preferably with a conical upper surface, provided with radial wings and rotating intermittently with a step-by-step movement in the bottom of the hopper in order to 70 bring the tobacco to the pocket in quantity sufficiently near constant to satisfy requirements.

Another object of the present invention is to provide means for smoothing the binder 75 as it is rolled about the bunch, to which end another feature of the invention consists in combining with the rolling lever, in position to coöperate with the apron as it passes over the bunch roller, a smoothing bar having 80 means whereby it is laid flat upon the rolling table prior to the commencement of the rolling action, but is laid against the bunch rollers, with the apron and binder intervening when the rolling action commences so 85 that the apron draws past the leaf in the direction opposite to that in which the leaf moves to the filler, and thereby smooths out the leaf.

My invention will be fully understood 90 upon reference to the accompanying drawings, in which,

Figure 1 is a side elevation, partly in section, of a machine of known type having my present improvements embodied therein; 95 Fig. 2 is a plan view of the hopper on an enlarged scale; Fig. 3 is a section on the line 3—3, Fig. 2; Figs. 4 and 5 are perspective views showing two positions of the smoothing bar; Fig. 6 is a detail view illustrating the rolling and smoothing action; and Fig. 7 is a detail view of the cam wheel which operates the plunger working in the discharge pocket.

The frame A with the operating mechanism B, the main hopper C, with the matrix slide D, the charging plunger E, the outer discharging plunger F, and the apron G, with its controlling levers g , g' may be constructed substantially as disclosed in patents 105 110 heretofore granted to me. The hopper C is preferably provided with a vertically elong-

gated or deepened pocket *c*, as described in my co-pending application, Serial No. 440,158, filed June 24, 1908.

In order to prevent the varying weight of the bulk of tobacco contained in the hopper *C* from having a distinct influence on the amount of tobacco fed into the pocket *c*, the hopper is provided with a guard 1, preferably in the form of a curved wall introduced into the hopper *C* in position to prevent the main bulk of tobacco standing above the pocket *c*. This guard, however, need not be of the particular construction disclosed. It is preferably provided with an opening 2, through which the tobacco is carried by the wings 3 on the rotating disk 4, and this opening 2 may be regulated in size by a vertically adjustable gate 5. The opening 2 admits to the discharge opening 20 or pocket *c*, a quantity of tobacco suitable to insure proper filling of the pocket and sufficiently near constant to maintain a suitable degree of uniformity in the weight or size of the bunches. In addition to the guard 1, 25 tobacco is further restricted by a barrier 6 projecting above the plane of the wings 3, so as to avoid tendency of the tobacco to become packed in the corner against gate 5.

By employing the particular form of guard 1 disclosed herein, a space is provided for the operation of the plunger *F*, and the feed may be observed at any time. But I do not limit myself to this particular form.

The conical bottom disk 4, with its wings 3, is intermittently rotated, step-by-step, by a pawl 7 carried by the matrix slide *D*, and engaging, in the forward direction, the ratchet wheel 8.

The slide *D* is reciprocated by a cam lever 40 in the usual manner, so as to bring the matrix *d* over the pocket formed in the apron to receive the measured charge of tobacco preliminary to rolling.

The particular construction of smoothing device selected to illustrate this feature of my invention is shown more clearly in Figs. 4, 5 and 6, and comprises the bar 9 having end mountings 10 pivoted at 11 to the rods 12, which are mounted to reciprocate in 45 bearings 13 on the rolling lever 14, and drawn normally rearward by the springs 15. The ends of the mountings 10 are curved as shown at 16. When the lever assumes the position shown in Figs. 1 and 4, 55 the ends of the rods 12 abut against the stops 17, and the bar 9 is permitted to lie upon the rolling table in position to permit the binding leaf to be laid upon it spaced apart from the rollers to admit the charge of tobacco between the bar and the rollers, upon the rolling apron and binder leaf; but when the lever 14 moves forward, springs 15 draw the rods 12, and through them the smoothing bar 9, rearward, during which motion 60 the curved ends 16 act as cams to raise the

bar 9, so that continued inward movement of rods 12 will cause the bar 9 to lay the leaf lightly against that part of the rolling apron which is passing around the bunching rollers 18 (of which there may be two or 70 one). Continued forward movement of the lever 14 will cause the rolling apron to brush against the leaf in the opposite direction to that in which it is feeding, and smooth it out, as it is wrapped around the bunch; see 75 Fig. 6.

Having thus described my invention, what I claim as new therein and desire to secure by Letters Patent is:—

1. In a cigar bunching machine, a main 80 receptacle, a supplemental receptacle, having a measuring device into which tobacco is fed, to determine the quantity of tobacco entering into the filler; means maintaining a substantially constant depth of tobacco 85 in said supplemental receptacle over said measuring device.

2. In a cigar bunching machine having a measuring opening and a hopper from which tobacco is fed to said measuring opening; a guard preventing a portion of the bulk of the tobacco from lying over the measuring opening, but permitting tobacco to feed laterally past the guard to the measuring opening, a rotary means for feeding the tobacco to the measuring opening, and a barrier extending above the plane of the rotary feeding means, in advance of the guard, and preventing the tobacco packing 95 against the guard. 100

3. In a cigar bunching machine, a hopper having a measuring pocket having an upwardly presented filling opening and a guard preventing the tobacco in the hopper lying over the filling opening of the pocket, 105 and having a lateral opening through which tobacco is admitted to the space above the pocket.

4. In a cigar bunching machine, a hopper having a measuring pocket, a guard preventing the bulk of the tobacco from lying upon the measuring pocket, having a lateral opening through which the tobacco is admitted to the measuring pocket, and a means for advancing tobacco through said 110 lateral opening to the measuring pocket. 115

5. In a cigar bunching machine, a hopper having a measuring pocket, a guard preventing the tobacco of the hopper from lying above the measuring pocket, having a lateral opening through which the tobacco is admitted to the measuring pocket, and a means for advancing tobacco through said lateral opening to the measuring pocket, comprising a rotary disk having peripheral wings passing successively through said lateral opening as the disk is rotated. 120 125

6. In a cigar bunching machine, a hopper having a measuring pocket, a guard preventing the bulk of the tobacco resting over 130

the measuring pocket, and having a lateral opening through which tobacco is fed to the measuring pocket, said guard being open upwardly above the measuring pocket, to 5 permit a plunger working through the guard above the measuring pocket.

7. A cigar bunching machine, having a matrix slide provided with a pocket, a vertically elongated measuring pocket through 10 which the pocket of the matrix slide is fed, a hopper containing tobacco to be fed to said measuring pocket, a guard in said hopper preventing the bulk of the tobacco resting over the measuring pocket, and having 15 a lateral opening through which tobacco is fed to the measuring pocket, and means for feeding tobacco through said lateral opening and maintaining a substantially constant depth of tobacco above the measuring 20 pocket.

8. In a cigar bunching machine having a bunching roller lever and a rolling apron, means coöperating with said rolling apron to smooth the binder leaf, comprising a bar 25 movable from a position lying upon the rolling table, to a position against the apron, and means automatically moving said bar from the former position to the latter as the rolling action commences, consisting of the 30 end mountings for the bar having cam-ends, the rods upon which said bar is pivoted, means drawing said rods inward as the roll action takes place, and means pressing said rods outward when the rolling lever assumes 35 a position to permit deposit of the tobacco upon the apron.

9. In a cigar bunching machine, having a bunching roller lever and a rolling apron, means coöperating with said rolling apron 40 to smooth the binder leaf, comprising a bar movable from a position lying upon the rolling table, to a position against the apron, and means automatically moving said bar

from the former position to the latter as the rolling action commences, comprising the 45 pivotally supported end mountings for said bar having cam-shaped ends adapted to impinge the rolling lever, and the reciprocating rods through which said mountings are supported, having springs drawing them inwardly and having relatively fixed abutments for forcing them outward. 50

10. A cigar bunching machine, comprising a measuring pocket, a hopper from which tobacco is fed to the measuring pocket, a guard 55 plate positioned within the hopper and forming a chamber above and in constant communication with the measuring pocket, said plate having an opening to permit a limited amount of tobacco to be fed from the hopper to the measuring pocket. 60

11. A cigar bunching machine, comprising a measuring pocket, a hopper from which tobacco is fed to the measuring pocket, a chamber directly over and in constant communication with said pocket and with said hopper, and adjustable means for determining the extent of communication between the hopper and said chamber. 65

12. A cigar bunching machine, comprising a hopper, a measuring pocket, a feeding means for conveying tobacco from the hopper to the measuring pocket, a guard plate secured to said hopper and forming a chamber above the measuring pocket, said guard 75 plate having an opening adjacent to the plane wherein the feeding means travels, and a vertically movable plate for regulating the size of said opening.

The foregoing specification signed at 80 New York city this third day of June, 1909.
